GOLF TEE

Kalman Spluvak, Cleveland, Ohio

Application January 25, 1955, Serial No. 483,965

8 Claims. (Cl. 273—212)

This invention relates as indicated to a novel golf tee, and more particularly to a tee adapted to be inserted in the ground on a true vertical line so that a golf ball supported thereby will always be properly positioned.

The game of golf is steadily becoming increasingly popular, and the operation of golf links and the instruction of beginners in the game have become large and profitable businesses. In order that the golfer may obtain consistent results when employing the proper stance, swing, and posture prescribed, it is essential that the ball should always be teed in a uniform and proper manner. If the tee is inserted into the turf in a somewhat inclined position, it may still support the golf ball while nevertheless interfering with proper engagement of the club head with the ball. It is, of course, also important that the tees should be constructed of material sufficiently tough to withstand a blow from the club, sufficiently visible to be readily found, and yet unlikely to damage the blades of a lawn mower when not found.

It is accordingly a principal object of my invention to provide a golf tee meeting the above requirements in a novel manner, and more particularly a tee which may quickly be inserted in an absolutely vertical direction so that the ball supported thereby will always be ideally placed without likelihood of interference of the tee with engagement of the club head with the ball.

Other objects of the invention will appear as the description proceeds.

To the accomplishment of the foregoing and related ends, said invention then comprises the features herein-after fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a vertical section through a tee embodying the principals of my invention;

Fig. 2 is a similar section through the head of another tee in accordance with my invention; and

Fig. 3 is a top plan view of the tee of Fig. 1.

Referring now more particularly to said drawing, my new tee may comprise a tapered stem or spike portion 1 terminating in a point 2 and flaring at its upper end 3 to provide an inner cavity 4 in the head portion. Such stem may be composed of transparent plastic material not readily breakable and containing a fluorescent die to enable it to be more readily discovered in the grass. Polystyrene plastic and cellulose acetate butyrate are suitable well-known commercially available plastics for my purpose. The head or cup proper 5 of my new tee is adapted to fit in the upper portion of cavity 4 defined by the flaring upper portion 3 of stem 1 and to be joined thereto by a suitable adhesive, solvent, or preferably by heat-sealing when thermoplastic materials are utilized. The upper surface of such head 5 is cupped or dished at 6 to provide the usual receptacle for the golf ball. In

2

the Fig. 1 embodiment, the opposed inner surface 7 of such head is concave so that the two concave surfaces are opposed to each other. The proper amount of liquid, ordinarily water W, may be placed in cavity 4 prior to sealing head 5 in place, but I will ordinarily prefer to inject the liquid as at 8 by means of a hypodermic needle and then to heat-seal the orifice formed thereby. The amount of liquid thus provided or injected will be insufficient entirely to fill cavity 4 and will leave a small air bubble which will center itself naturally beneath concave surface 7 of head 5 when the tee is held in perfectly vertical position with point 2 downwardly disposed for insertion in the ground. A very small amount of a commercially available wetting agent such as sodium green acid sulphonate, sodium or potassium lauryl sulphate, and ethylene oxide condensation products with phenols, alcohols, and carboxylic acids will preferably be added to the water to ensure rapid movement of the bubble B when the tee is tilted.

In the modification illustrated in Fig. 2 of the drawing, a capsule 9, ordinarily of thin walled plastic, will be largely filled with water but with an air bubble B left therein, and such capsule may be inserted in cavity 4 and retained by closely fitting cap or head 10 adhered or welded to the flaring upper portion of the tee stem. As shown, the inner surface of the head 10 may be convex and should engage capsule 9 to assist in holding such capsule in properly centered position.

The manner of use of my new tee will be obvious from the foregoing. The golfer will insert the same in the turf in the usual manner but taking care that the bubble B is properly centered as viewed through the transparent cup or head portion 5. He may then be assured that the golf ball is precisely properly supported without danger of interfering with engagement of the club head with the ball.

It is preferred that the entire tee be of resilient synthetic plastic (e. g. polyethylene) but obviously the stem portion may be of wood or aluminum, if desired. The head must be sufficiently transparent that the liquid therein is readily visible when viewed from the top and capsule 9 must also be transparent. The additional air space in the Fig. 2 form is sufficient to ensure that the tee will float if inadvertently knocked into a water hazard. The bubble in the head should preferably be of smaller diameter than the window in the top of the head of the Fig. 1 form for more accurate locating. Cross-hairs may be scribed in the top of such head but are not necessary.

The liquid employed may desirably be colored to contrast with the plastic and better to outline the bubble. If the Fig. 2 form is employed without capsule 9, the convex inner surface of the upper head portion will cause the bubble in the cavity to form a ring when the tee is held vertically and such ring will break when the tee is tilted. Despite the attractive appearance and improved utility of my new tee, it is inexpensive of manufacture and adapted to production in large quantity. When capsule 9 is employed, it will preferably be globular in form.

Other modes of applying the principle of the invention may be employed, change being made as regards the details described, provided the features stated in any of the following claims or the equivalent of such be employed.

I therefore particularly point out and distinctly claim as my invention:

1. A golf tee comprising a fluorescent plastic tapering stem having a hollow outwardly flaring head portion, a transparent plastic head joined and sealed to said flaring head portion of said stem and closing off the hollow cavity therein, said head being concave in its upper outer surface to receive and support a golf ball thereon and also concave in its inner surface defining the upper wall

3

of such cavity, colored water contained in such cavity just insufficient to fill the same and therefore leaving an air bubble adapted naturally to position itself centrally of said head when said stem is held in vertical position for insertion in the ground, and a small amount of a wetting agent dissolved in said water to facilitate rapid change in the position of such bubble as said stem and head are tilted.

2. A golf tee comprising a plastic stem having a relatively wide upper portion with a hollow in the upper surface thereof, a transparent plastic head joined and sealed to said upper portion of said stem and closing off the hollow cavity therein, said head being formed with a hollow in its upper outer surface to support a golf ball thereon, and liquid in such hollow cavity just insufficient to fill the same and therefore leaving an air bubble therein adapted to indicate by its position as viewed through said transparent head when the tee is held in exact vertical position.

3. A plastic golf tee having a stem portion and a wider head portion formed to support a golf ball thereon, characterized by the provision of a hollow cavity within said head and liquid therein just insufficient to fill the same and therefore leaving an air bubble adapted to indicate by its position when the tee is held in exact vertical position, the top of said head being transparent to permit such liquid and bubble to be thus visible.

4. A golf tee having a stem portion and a wider head portion formed to support a golf ball thereon, characterized by the provision of a hollow cavity within said head and liquid therein just insufficient to fill the same and therefore leaving an air bubble adapted to indicate by its position when the tee is held in exact vertical position, the top of said head being transparent to permit such liquid and bubble to be thus visible.

5. A golf tee comprising a fluorescent plastic tapering stem having a hollow outwardly flaring head portion, a transparent plastic head joined and sealed to said flaring head portion of said stem and closing off the hollow cavity therein, said head being concave in its upper outer surface to receive and support a golf ball thereon, a transparent globular plastic capsule fitted tightly centrally within such cavity, colored water contained in said capsule just insufficient to fill the same and therefore leaving an air bubble adapted naturally to position itself cen-

trally of said head when said stem is held in vertical position for insertion in the ground, and a small amount of a wetting agent dissolved in said water to facilitate rapid change in the position of such bubble as said stem and head are tilted.

6. A golf tee comprising a plastic stem having a relatively wide upper portion with a hollow in the upper surface thereof, a transparent plastic head joined and sealed to said upper portion of said stem and closing off the hollow cavity therein, said head being formed with a hollow in its upper outer surface to support a golf ball thereon, a transparent capsule fitted tightly within such cavity, and liquid in said capsule just insufficient to fill the same and therefore leaving an air bubble therein adapted to indicate by its position as viewed through said transparent head when the tee is held in exact vertical position.

7. A golf tee having a stem portion and a wider head portion formed to support a golf ball thereon, characterized by the provision of a transparent capsule enclosed within said head and liquid therein just insufficient to fill the same and therefore leaving an air bubble adapted to indicate by its position when the tee is held in exact vertical position, the top of said head being transparent to permit such liquid and bubble to be thus visible.

8. A golf tee comprising a colored plastic stem having a relatively wide upper portion with a hollow in the upper surface thereof, a transparent plastic head joined and sealed to said upper portion of said stem and closing off the hollow cavity therein, said head being formed with a hollow in its upper outer surface to support a golf ball thereon, and liquid in such hollow cavity just insufficient to fill the same and therefore leaving an air bubble therein adapted to indicate by its position as viewed through said transparent head when the tee is held in exact vertical position, such liquid being of a color contrasting the color of said stem.
